UNITED STATES PATENT OFFICE.

GEORGE FERGUSON, OF LOS ANGELES, CALIFORNIA.

FLYING MACHINE.

Refiled for abandoned application Serial No. 447,196, filed August 6, 1908. This application filed October 18, 1924. Serial No. 744,613.

This specification is refiled for abandoned application filed August 6, 1908, Serial Number 447,196, of which this is a substantial duplicate.

5 This invention relates particularly to a novel device adapted for flying machines, wind mills, propellers, etc., in which the operating principle of a bird's wing is adopted and carried out mechanically to such 10 an extent as to enable the support and flight of the frame of a flying machine, or the propulsion of wind mills, propellers, etc., equipped with my improved form of device.

A basic object of this invention is to provide 15 a novel form of device that will automatically adjust itself to the varying conditions of the prevailing winds, and mechanism is provided whereby the operator is enabled to control the force exerted upon the 20 wings or blades so as to operate and direct the device in any desired direction, position or movement of the device, such as soaring, hovering, etc.

25 Heretofore supporting wings of this character have been made with a rigid construction, or at least as rigid as the large and light construction would allow. The present wing differs radically from the above style of wing by being provided with a pivotal 30 adjustment of its main longitudinal frame which acts similarly to the pivotal adjustment of a bird's wing and it also is provided with adjustable resilient means for holding the wind surface of the wing against the 35 wind.

This construction is embodied in the device shown in the accompanying drawings and, although a larger part of the invention resides in any one of the wings, enough 40 mechanism is shown and will be described to set forth a clear idea of the construction and operation of a complete machine.

In the accompanying drawings forming a 45 part of this specification:

Figure 1 is a plan view of a machine embodying the principles of my invention;

Figure 2 is a side elevation of the same with parts broken away for clarity of illustration;

50 Figure 3 is a sectional elevation taken on line 3-3 of Figure 2;

Figure 4 is a detail view showing the gearing of the propelling motor;

Figure 5 is an enlarged detail plan view

55 showing the base mechanism of the upper wings;

Figure 6 is an end elevation of the same;

Figure 7 is an enlarged sectional plan view 60 of the joint between one of the longitudinal wing frames and a transverse wing frame;

Figure 8 is an enlarged sectional view 65 taken on line 8-8 of Figure 5;

Figure 9 is a plan view showing the base mechanism of the lower or propelling wings;

Figure 10 is a plan view of the steering 65 rudder;

Figure 11 is a side elevation of the same and its operating parts.

In the drawings, 20 designates the main longitudinal frame of the flying machine, a 70 plurality of supporting standards 21 depending from the frame and supporting the lower mechanisms and platforms. Platform 22 supported at the lower ends of standards 21 75 is preferably formed of a tubing frame 23 preferably provided with a wire netting floor 24. This platform supports motor 25 and affords room for the operators of the machine.

80 Mounted upon frame 20 in the manner illustrated in detail in Figure 5 is a plurality of supporting wings 26. The frame may be of any desired length and any number of these supporting wings placed along it. Wings 26 are constructed with a longitudinal 85 frame 27 which is turned at right angles to its inner end to form a lever 28 by means of which the adjustment of the wing is accomplished through the medium of the adjusting mechanisms to be hereinafter explained. 90

The longitudinal frame 27 is flattened as at 29 at a point close to its inner end, a cross section at this point being illustrated in Figure 8, so that a lateral resiliency is added at this point.

95 Further out towards its outer end the frame is made into a curved cross section, as is indicated in Figure 7, so that additional strength is imparted. Mounted on frame 20 is a number of wing supporting frames 30, one for each pair of wings.

100 These frames are made in a general U-shape, as illustrated in Figure 6, and wing supporting shafts 31 pass through bearings 32 supported at their upper ends. Shafts 31 105 project outwardly and wing frames 27 are pivotally mounted on the shafts as illustrated in Figure 5, collars 33 holding the wing frames in place. The ends of levers

28 are joined by a connecting rod or bolt 34 and rods 35 connect the adjacent wings together, so that they may all be adjusted simultaneously. To one of bolts 34 an operating rod 36 is connected, being secured at its other end to a bell crank lever 37 pivoted at 38 to one of standards 21. A downwardly extending rod 39 is secured to one arm of the lever. The other arm of the lever is provided with an adjusting wheel 40 mounted between arms 40 on standard 21. By rotating wheel 40 the inclination of the longitudinal wing frames may be changed as desired.

15 Pivots mounted on each of the longitudinal wing frames as at 40' in Figure 7 is a plurality of transverse frames 41 constructed of any suitable material and extending transversely and rearwardly from the longitudinal frames. The transverse frames are made of proper length to afford the desired configuration to the body portion or wind surface of the wing which is formed of any suitable fabric 42, stretched under the longitudinal and transverse frames. These transverse frames may be either curved in any desired configuration or they may be straight as experience dictates. Journaled at 43 on longitudinal frames 27 and extending over the transverse frames are stirrups 44. These stirrups are connected together by means of a sectional shaft 45 with interposed spring connections 46. The innermost section of shaft 45 is preferably formed as a reduced extension of pivot shaft 31 which is provided on its inner end with a worm gear 46'. A pair of longitudinal adjusting shafts 47 are in bearings 48 and extend along keel 20, being operated through the medium of sprocket wheels 49 and sprocket chains 50 passing downwardly and each connected to a hand wheel 51 mounted on one of standards 21 within accessible distances from platform 22. These shafts carry worms 52 which mesh with and drive worm gears 46' so that upon any rotation of hand wheel 51 the resilient adjusting shafts will be turned on all the supporting wings alongside of keel 20. It is desirable that the resilient pressure of stirrups 44 downwardly upon transverse frames 41 shall be independently adjustable on each side of the machine as the guiding of the machine is accomplished to a great extent by the change of inclination of the wing surfaces on each side. It will be seen that by an appropriate rotation of hand wheel 51 the wind surface of the wing may be forced further from the horizontal or it may be allowed to be blown backwardly and upwardly closer to the horizontal. Frame 20 is extended to any desired length to support the desired number of wings 26. Upon its rear ends as shown in Figures 1, 10 and 11, is mounted a horizontal rudder 60. This rudder is pro-

vided with a pivotal shaft 61 extending longitudinally of the rudder, the shaft being mounted in bearings 62 on frame 20 of the ship. A transverse arm 63 is mounted on shaft 61 and steering cable 64 is attached to the ends of arm 63 and passes downwardly and over a pulley 65 rotated through the medium of a hand wheel 66. By turning hand wheel 66 rudder 60 may be inclined transversely to any desired degree.

In the operation of the parts of the machine so far described, the machine is placed head on to a wind and the inclination and resilient downward pressure of supporting wings 26 adjusted. When a correct adjustment has been reached so that a large enough component of the wings' horizontal movement and pressure has been thrown into the vertical direction, the machine will be raised off the ground. The weight of the machine below the starting wings is sufficient to balance it and prevent it from being overturned by the wind. As long as a steady upright position is thus kept the machine will be raised by the wings and when the desired elevation has been reached the inclination and the resilient downward pressure of the wings is lessened. By this adjustment a larger proportion of pressure is thrown into the rearward component of the wings and the machine ceases its upward flight and immediately moves head into the wind. The action in this regard is similar in principle to the sailing of a boat into the wind, but a great improvement is made by the resilient construction of the wing and the resilient downward pressure of the wind surfaces. This resilient downward pressure provides for varying wind intensities and keeps the machine moving uniformly. For guiding the machine in a horizontal plane the resilient downward pressure of the wind surface is changed on one side or the other of the machine. It will be seen that this change will cause one side of the machine to move forward more rapidly than the other. To keep the machine on an even keel during these operations, rudder 60 is especially provided. If the machine tilts transversely the rudder may be inclined in an appropriate direction to bring the machine back to its normal position.

To provide for times when there is not a suitable breeze or when it is desired to move in some other direction than into the wind I have provided a propelling apparatus which is mounted on the frame of the machine and which will propel the machine forwardly so that the above described operations of the supporting wings will take place. This propelling apparatus comprises a number of small propelling wings 70 of a construction similar to that of the supporting wings 26 mounted in pairs upon longitudinal operating shafts 71 and 71^a, mounted

in bearings 72 on standards 21. These propelling wings are constructed with longitudinal frames 27 of a character similar to frames 27^a of the supporting wings and with transverse frames 41^a resiliently pressed downwardly through the medium of stirrups 44^a, the frames being covered by the suitable fabric 42^a. Adjusting levers 28^a of these wings on upper shaft 71^a are connected together by means of a rod 73 and the levers of the lower wings are connected to those of the upper wings by rods 74 having resilient springs 75 interposed to allow of the heavy movement necessary between the sets 15 of wings on the upper shaft and those on the lower shaft. One of the sets of wings on the lower shaft is adjusted directly from the bell crank lever 76 operated by a hand wheel mechanism 77, a spring connection 20 78 being interposed so that the wings may move with relation to the frame. Longitudinal frames 27^a of these wings are pivoted directly on shafts 45^a which extend through shafts 71, collars 79 being provided 25 to prevent any longitudinal movement of the wing frames on the shafts. Hand wheels 80 are mounted on shafts 45^a and spring detents 81 serve to hold the wheels and shafts 45^a in any desired position. By 30 this means any amount of torsion may be placed upon shafts 45^a and the wind surfaces of the wings forced downwardly with any desired pressure.

Operating shafts 71 are provided with arms 90 which are connected by connecting rods 91 to cranks 92 mounted on shafts 93 geared to engine shaft 94. By means of the relative arrangement illustrated in Figure 3, it will be seen that the wings on one 35 of the shafts 71 will be moving upwardly on one side while the wings on the other shaft are moving downwardly on the same

side. Thus an alternate movement is provided in such a manner that there is always one set of wings moving downwardly on each side of the machine and the whole machine is thereby kept in equilibrium.

From the foregoing description it will be seen that I have provided a flying machine which utilizes the bird principles of flying. 50 When the machine is moving into the wind there is no need for any motor propelling device, the force of the wind moving the machine along. When, however, it is desired to move with the wind or in a still atmosphere, the motor propelling apparatus is then utilized.

Although I have shown and described herein but one form of flying machine embodying my invention, it will be understood that various changes and modifications may be made without departing from the spirit of the invention and the spirit and scope of the appended claims.

I claim as my invention:

1. Flying machine construction comprising a longitudinal wing frame mounted to be pivotally adjustable, a transverse wing frame pivotally mounted on the longitudinal frame and adjustable resilient means for 70 changing the angle of incidence of said transverse frame and for holding said transverse frame in position.

2. A flying machine comprising a main frame, longitudinal wing frames pivotally mounted on the main frame, and extending transversely therefrom, transverse wing frames pivotally mounted on the longitudinal wing frames, and resilient means to adjust the position of the transverse frames, 75 the adjusting means for all the wings on each side of the main frame being inter-connected.

GEORGE FERGUSON.
